UNITED STATES PATENT OFFICE.

LEONARD M. RANDOLPH, OF NEWARK, NEW JERSEY, ASSIGNOR TO HIGH SPEED ENGINE CORPORATION, OF NEWARK, NEW JERSEY, A CORPORATION OF DELAWARE.

ROTARY ENGINE.

1,268,771.

Specification of Letters Patent. Patented June 4, 1918.

Application filed June 12, 1916. Serial No. 103,223.

To all whom it may concern:

Be it known that I, LEONARD M. RANDOLPH, a citizen of the United States, a resident of the city of Newark, county of Essex, 5 State of New Jersey, have invented a new and useful Improved Rotary Engine, of which the following is a specification.

My invention relates more particularly to a rotary engine of that type which is equally 10 adapted to be driven by steam or any other elastic fluid, or by reversing, the functions of the steam inlet and exhaust outlet, to be used in a reverse way as a pump or an air compressor; and while the word steam is here- 15 after used as a designation of the motive force employed to drive the engine, when used as a motor, this term is to be construed, throughout the patent, to include any other elastic fluid as a substitute therefor, as may 20 be practicable or convenient.

Among other objects of my invention are: to provide rotary engines of the type mentioned, with solid power shafts, driven by a rotary piston mounted thereon, thus eliminating drums and transmission gear, and 25 with variable cut off and reversing valves not contacting with moving parts; to eliminate frictional or rubbing surfaces, between the rotary and adjacent surfaces, while providing 30 means for securing substantially steam tight joints between the rolling cylinder heads, or abutments and the peripheral faces of the piston leaves and of the intervening sections of the piston; also to provide a uniform, 35 maximum steam supply to the compartments of the piston chamber, with a minimum frictional loss through a steam chamber or reservoir, common to all of the supply ports, into which the steam is directly admitted, through an opening in the 40 casing and to shorten the conduits therefrom to the piston chamber, by locating them in the recessed faces of the cylinder heads, or valvular abutments; also to eliminate back 45 pressure in the exhaust by means of an exhaust chamber, common to all of the exhaust ports, which, with the exhaust conduits, are located in the rear sections of the cylinder heads, or abutments, and from thence to exhaust 50 directly through an exhaust outlet in the casing; also to increase the relative horse-power of the engine for weight, by providing means to secure a maximum number of steam

impulses for each revolution of the piston; also to render the operation of the machine 55 automatic, by providing means for operatively positioning the pistons, or one of them, to take steam at any point in the cycle, in at least one compartment, through the piston leaves being unequal in number to the compartments; also to adapt the engine for multifarious uses and functions by providing threaded openings in the casing adapted for pipe connections with sources of steam, 65 water or air supply, under valvular control, whereby the functions of the openings in the casing, for the steam inlet and the exhaust outlet may be reversed and the engine operated as a pump, or an air compressor, as desired. 70

Such of the improvements, hereinafter specified, as are not claimed in this application are the subjects of separate applications for United States Letters Patent.

Having thus generally described some of 75 the objects of my invention, I will now more particularly describe the latter by reference to the annexed drawings which illustrate a machine embodying my invention and in which similar reference characters indicate 80 identical parts. In the drawings:

Figure 1 is a longitudinal section, cut through the center of the machine, but showing the power shaft in perspective.

Fig. 2 is a cross section cut through the 85 machine at 2-2 on Fig. 1.

Fig. 3, is a detail showing the valve mechanism and the gear controlling it.

Figs. 4, 5, and 6, are detail views of the 90 rolling cylinder heads, illustrating and showing the leaves of the rotary piston positioned at different points in the cycle. They are sections cut through the lines a-a on Fig. 7.

Fig. 7, is a perspective view of a rolling cylinder head, with the steam and exhaust 95 ports and conduits indicated.

Fig. 8, is a cross section of the same, cut through the line a-a of Fig. 7.

Fig. 9, is a detail showing the mechanism for positioning the variable cut off and reversing valve. 100

The power shaft 1, is solid throughout and is mounted on ball bearings 2, 2, which are secured in the heads of the casing 3, as shown. The longitudinal adjustment of the 105 power shaft 1, to secure a close running fit,

without contact between the adjacent parts of the rotary piston 4, and the conical wall of the piston chamber and the rolling cylinder heads or abutments 6, and thus to provide steam tight piston joints, is secured by the check nuts 1^a, 1^a, by which the power shaft is positioned, as shown in Fig. 1. Keyed to the power shaft 1, and imparting motion to it, is the rotary piston 4, shown in detail Figs. 4, 5, and 6, which is provided with two leaves 5, 5. These revolve freely within the piston chamber 8, and the recessed sections 12, in the faces of the three rolling cylinder heads 6, without actually contacting therewith.

The rolling cylinder heads 6, are mounted on ball bearings 7, 7, to rotate laterally and are adjustable longitudinally to permit of a close running fit and a steam tight joint, without contact with adjacent surfaces, the cylinder head and recesses within which they are housed, being conical, such adjustment is secured by means of the balls 7^a, and the set screws 7^b, and operatively divide the piston chamber 8, which is an annular steam chest, into three compartments, by supplying abutments at timed intervals, as shown in Figs. 4, 5, and 6, to each of which compartments steam is successively supplied, to drive the piston leaves and from which the steam is exhausted after doing work. The recessed sections 12, in the faces of the rolling cylinder heads 6, are crescent shaped, and are timed, as hereafter explained, to provide open ways for the passage of the piston leaves 5, 5, from one compartment to another, in their progressive advance, and by their timed rotary movements to immediately on the passage of a leaf therethrough close the way by presenting a solid section, to close the compartment and furnish an abutment behind such progressing piston leaf. This is accomplished by means of a gear 9, keyed in the power shaft 1, at 10, as shown in Fig. 1, which intermeshes with the gear 11, carried on the rolling cylinder heads 6, as shown in Fig. 1. The respective gears are arranged to so register with each other, that the related motions of the respective cylinder heads shall be timed with the progressive advance of the respective piston leaves 5, 5, to successively present the recessed sections 12, of the cylinder heads 6, to the respective advancing piston leaves, so positioned as to permit the passage thereof, as heretofore stated, and to close the aperture on the disengagement of a piston leaf from such recessed section, and also to open the exhaust port 13, of such cylinder head 6, as shown in Figs. 4, and 5, to exhaust the compartment from which the piston leaf has just been disengaged. Fig. 5, shows two exhaust ports open, while in Fig. 4, the exhaust port in the upper cylinder head is shown as about to engage in the recess in

the casing to exhaust the compartment from which the piston leaf, in its clockwise advance, has just been disengaged.

The steam inlet 14, in the casing 3, is shown as threaded for a pipe connection, as 70 is the exhaust outlet 28, and by means of such pipe connections the functions of the inlet and outlet may be reversed, and the engine operated as a pump, or air compressor, being driven from a foreign source of 75 power.

The steam inlet 14, opens in an annular steam chamber 15. In this chamber is located the variable cut off and reversing valve system, which comprises the valve 80 rings 17, 18, and 19, movably mounted on the sleeves 3^a of the casing 3, shown in detail Figs. 2 and 3, and their motions controlled through the segmental gear 20, with which they are each provided, this gear intermeshes with a spur gear 21 mounted on the casing 3, inclosing the power shaft 1, as shown; the spur gear in turn intermeshes with a segmental gear 22, carried by the shaft 23 shown in detail Figs. 3, and 9, at 90 the outer end of which is provided a handle 23^a which is furnished with a pin adapted to engage in the openings 23^b in the segmental frame shown in Fig. 9, and retained in position by a spring indicated in the 95 drawing. The valves 16, 16, in the valve rings 17, 18, and 19, may thus be adjustably engaged with the ports 24, and 24^a, in the casing sleeves 3^a, to vary the steam cut off, or may be thrown over from engagement 100 with the ports 24, to engage with the ports 24^a, to reverse the direction of the rotation of the piston leaves 5, 5, or vice versa, as may be desired.

In Fig. 1, the shaft 23, is shown without 105 any connections, and, as is obvious a connection can be made with a governor, and the steam supply thus automatically regulated. The valves 16 in the respective valve rings, are shown in a neutral position in 110 Fig. 2, while in Fig. 3, the valve 16, is shown positioned to register with the inlet, or port, 24, in the casing sleeve 3^a, and to supply steam to drive the engine in a clockwise direction. By throwing the valve ring over 115 and causing the corresponding valve 16, to register with the inlet 24^a, the steam will drive the engine in the reverse direction.

The rolling cylinder heads 6, are provided with ports, 25, and conduits therefrom 120 to the recessed sections 12, as shown.

The ports 25, receive steam through the valves 16, of the respective valve rings, through either the inlet, or port, 24, or 24^a and are timed in registering therewith, to 125 admit steam into the compartments behind the leaves 5, 5, of the revolving piston 4, as the abutments behind them are successively closed, by the volute motion of the respective cylinder heads as already explained. 130

The duration of the periodic intervals of steam supply, through the respective ports 25, is governed by the degree of accuracy with which the valves 16, of the valve rings 5 register with the inlets or ports 24, or 24^a, as the case may be, and this is adjustably determined by positioning the handle 23^a, to cut off the steam, at any point desired, the rest of the piston travel thereafter being 10 made on expansion.

The rotary piston thus receives six separate impulses, three for each piston leaf, during each revolution, and its action is automatic, one of the ports 25, being always, 15 either operatively engaged, or past the point of engagement.

Figs. 7, and 8, show the exhaust ports in the rear of the cylinder heads 6, and leading to the exhaust conduits 26, which open at the 20 other end into the exhaust chamber 27, these conduits are indicated on Fig. 7, and one of them is shown in Fig. 1. From the chamber 27, the steam is exhausted through the outlet 28, in the casing 3.

25 The system of steam circulation through the engine is as follows:

The steam is admitted to the steam chamber 15, through the inlet 14, in the casing 3, and thence passes intermittently, at periodic 30 intervals, through the respective valves 16, registering with one, or the other, of the ports, or inlets, 24, or 24^a, in the casing sleeve 3^a, to the ports 25, in the cylinder heads 6, and thence through the conduits in 35 the latter connecting the same with the recessed sections 12, in the faces thereof, to the respective compartments of the piston chamber 8; thence it is exhausted through the exhaust ports 13, and the connecting conduits 40 26, in the rear of the rolling cylinder heads 6, into the exhaust chamber 27, and through it and the exhaust outlet 28, in the casing 3, to the atmosphere, or a condenser.

One of the piston leaves is always operationally positioned to take steam, thus rendering the operation of the engine, whether for the generation of power, or as a pump, or air compressor, entirely automatic. The valves are thrown from their neutral position, shown in Fig. 2, to an operative position, as shown in Fig. 3, or the reverse thereof, the point of cut off being regulated as desired, and the engine will continue to operate until steam is cut off. If used as a 55 pump, or air compressor, the operation is controlled by the valve system in the same manner.

Having thus specified, described and shown the same, I claim as novel and my invention:

1. In a rotary engine in combination, a valve carrying member having an annular conical piston chamber with conical recesses therein, a number of conical, valvular abutments, adjustably mounted in such recesses,

dividing such chamber into a number of compartments a solid, cylindrical, adjustably mounted piston carrying member, a conical piston provided with leaves, in number unequal to the valvular abutments, permanently secured to such last named member to rotate within such chamber, means for the longitudinal adjustment and positioning of such valvular abutments and such piston to secure steam tight joints, without contact of any of such parts with adjacent surfaces, and means for admitting steam through such valvular abutments to the piston chamber, so timed as to continuously drive such piston. 75

2. In a rotary engine in combination, a valve carrying member having an annular conical piston chamber with recesses therein, a number of conical valvular abutments adjustably mounted in such recesses, dividing 85 such chamber into a number of compartments, a solid, cylindrical, adjustably mounted piston carrying member, a conical piston provided with leaves, in number unequal to the valvular abutments, permanently secured to such last named member, to rotate within such chamber, means for the longitudinal adjustment and positioning of such valvular abutments and such piston to secure steam tight joints, without contact of any of such parts with adjacent surfaces and means for admitting steam through such valvular abutments to the piston chamber, so timed as to continuously drive such piston. 90

3. In a rotary engine, in combination, a valve carrying member having a conical, annular piston chamber with recesses therein, a number of conical valvular abutments, adjustably mounted in such recesses, dividing 105 such chamber into a number of compartments, a solid, cylindrical, adjustably mounted piston carrying member, a conical piston provided with leaves, in number unequal to the valvular abutments, permanently secured to such last named member, to rotate within such chamber, means for the longitudinal adjustment and positioning of such valvular abutments and such piston to secure steam tight joints, without contact of any of such parts with adjacent surfaces and means for admitting steam through such valvular abutments to the piston chamber, so timed as to continuously drive such piston. 110

4. In a rotary engine, in combination, a valve carrying member having an annular, conical piston chamber with conical recesses therein, a number of conical valvular abutments, adjustably mounted in such recesses, 115 dividing such chamber into a number of compartments, a solid, cylindrical, adjustably mounted piston carrying member, a conical piston provided with leaves, in number unequal to the valvular abutments, per- 120

- 4
- manently secured to such last named member, to rotate within such chamber, means for the longitudinal adjustment and positioning of such valvular abutments and such 5 piston to secure steam tight joints, without contact of any of such parts with adjacent surfaces and a gear connecting such shaft and such abutments, so timed that steam is admitted to the chamber through such abutments to continuously drive such piston. 10
5. In a rotary engine, in combination, a valve carrying member having an annular, conical piston chamber with conical recesses, therein, a number of conical, valvular abutments mounted in such recesses, dividing such chamber into a number of compartments, a cylindrical piston carrying member, a conical piston provided with leaves, in number unequal to the valvular abutments, permanently secured to such last named member to rotate within such chamber, means for the longitudinal adjustment of said valvular abutments and such piston to secure steam tight joints, without contact of any of such parts with adjacent surfaces and means for admitting steam through such valvular abutments to the piston chamber, so timed as to continuously drive such piston. 20
- 25
6. In a rotary engine, in combination, a valve carrying member having an annular piston chamber with recesses therein, a number of valvular abutments mounted in such recesses, dividing such chamber into a number of compartments, a solid, cylindrical piston carrying member, a piston provided with leaves, in number unequal to the abutments, permanently secured to said last named member, to rotate within such chamber, recesses, abutments and piston having suitable contours for adjustably positioning such abutments and piston to form steam tight joints, without contact with adjacent surfaces, means for their longitudinal adjustment for such purpose and means for admitting steam through such valvular abutments to such chamber, so timed as to continuously drive such piston. 30
- 40
7. In a rotary engine, in combination, a valve carrying member having an annular piston chamber with recesses therein, a number of valvular abutments mounted in such recesses, dividing such chamber into a number of compartments, a solid, cylindrical, piston carrying member, a piston provided with leaves, in number unequal to the abutments, permanently secured to said last named member, to rotate within such chamber, recesses, abutments and piston having suitable contours for adjustably positioning such abutments and piston to form steam tight joints without contact with adjacent surfaces, means for their longitudinal adjustment for such purpose, means for admitting steam through such valvular abutments to such chamber, so timed as to continuously drive such piston. 45
- 55
8. In a rotary engine, in combination, a valve carrying member having an annular piston chamber with recesses therein, a number of valvular abutments mounted in such recesses, dividing such chamber into a number of compartments, a solid, cylindrical, piston carrying member, a piston provided with leaves, in number unequal to the abutments, permanently secured to said last named member, to rotate within such chamber, recesses, abutments and piston having suitable contours for adjustably positioning such abutments and piston to form steam tight joints, without contact with adjacent surfaces, means for their longitudinal adjustment for such purpose, means for admitting steam through such valvular abutments to such chamber, so timed as to continuously drive such piston, and valve rings adjustably controlling steam ports in the valvular abutments to reverse the engine. 50
9. In a rotary engine, in combination, a valve carrying member having an annular piston chamber with recesses therein, a number of valvular abutments mounted in such recesses, dividing such chamber into a number of compartments, a solid, cylindrical, piston carrying member, a piston provided with leaves, in number unequal to the abutments, permanently secured to said last named member, to rotate within such chamber, recesses, abutments and piston having suitable contours for adjustably positioning such abutments and piston to form steam tight joints, without contact with adjacent surfaces, means for their longitudinal adjustment for such purpose, means for admitting steam through such valvular abutments to such chamber, so timed as to continuously drive such piston and means for variably cutting off the steam supply. 55
10. In a rotary engine, in combination, a valve carrying member having an annular piston chamber with recesses therein, a number of valvular abutments mounted in such recesses, dividing such chamber into a number of compartments, a solid, cylindrical, piston carrying member, a piston provided with leaves, in number unequal to the abutments, permanently secured to said last named member, to rotate within such chamber, recesses, abutments and piston having suitable contours for adjustably positioning such abutments and piston to form steam tight joints, without contact with adjacent parts, means for admitting steam through such valvular abutments to such chamber, so timed as to continuously drive such piston, and valve rings adjustably controlling steam ports in the valvular abutments to vary the steam cut off. 60

steam through such valvular abutments to such chamber, so timed as to continuously drive such piston and means for adjustably controlling steam ports in such abutments 5 to vary the steam cut off.

11. In a rotary engine, in combination, a valve carrying member, having an annular piston chamber with recesses therein, a number of valvular abutments mounted in such 10 recesses, dividing such chamber into a number of compartments, a solid, cylindrical piston carrying member, a piston provided with leaves, in number unequal to the abutments, permanently secured to the last 15 named member, to rotate within the piston chamber; the latter, the recesses, abutments and piston having suitable contours for adjustably positioning such abutments and piston to form steam tight joints, without contact with adjacent surfaces, means for their 20 longitudinal adjustment for such purpose, means for admitting steam through such valvular abutments to such chamber, so timed as to continuously drive such piston 25 and means for adjustably controlling steam ports in such abutments to reverse the engine.

12. In a rotary engine, in combination, a valve carrying member having an annular 30 piston chamber with recesses therein with conical contours, a number of conical valvular abutments mounted in such recesses for longitudinal adjustment, each being provided with a concave way, or recess in its 35 front section, an inlet valve connecting a port in the periphery of the abutment, near the conical base, with the extremity of such recess or way, an exhaust outlet extending longitudinally in the rear section thereof, 40 the piston chamber being divided into a number of compartments by such abutments, a solid, cylindrical, piston carrying member having a piston with leaves, in number unequal to the abutments, permanently secured 45 thereto, to rotate in such chamber, means for the longitudinal adjustment of such piston and means for so timing the admission of steam to the chamber as to continuously drive such piston, the rotary parts being 50 adapted on such adjustment to form steam

tight joints without contact with adjacent parts.

13. In a rotary engine, in combination, a valve carrying member having an annular piston chamber with recesses therein, a number 55 of valvular abutments mounted in such recesses for longitudinal adjustment, dividing such chamber into a number of compartments, a piston carrying member, comprising a solid shaft, a piston permanently secured thereto, to rotate in such chamber, having leaves, in number unequal to the abutments, such piston being adjustably positioned by means of threaded sections on said shaft, near the bearings and check nuts fitted to 60 such sections and bearing on the valve carrying member, the piston and abutments being adapted to adjustably form steam tight joints, without contact with adjacent surfaces, and means for admitting steam 65 through said abutments to said chamber, so timed as to continuously drive said piston.

14. In a rotary engine, wherein the rotary parts are adapted to form steam tight joints without contact with adjacent surfaces, a 70 steam circulation system wherein the steam is admitted through inlet valves in a number of abutments, opening, through concave ways, or recesses in the faces thereof to the compartments, formed by such abutments, 75 in an annular piston chamber, having recesses in which such abutments are mounted, such steam valves being so timed, by gears connecting such abutments with a piston shaft, as to continuously drive a piston 80 permanently mounted on the latter to rotate within such chamber, such piston being provided with leaves, unequal in number to the abutments and adapted to receive such timed steam impulses, and wherein such steam is 85 exhausted through exhaust outlets extending from such chamber longitudinally through the rear sections of such abutments and the respective functions of such inlets and outlets being individual to each.

LEONARD M. RANDOLPH.
